UNITED STATES PATENT OFFICE.

ERICK G. WALLINDER, OF DULUTH, MINNESOTA.

RAILROAD-RAIL JOINT.

1,411,317.

Specification of Letters Patent. Patented Apr. 4, 1922.

Application filed May 31, 1921. Serial No. 473,817.

To all whom it may concern:

Be it known that I, ERICK G. WALLINDER, a citizen of the United States, residing at Duluth, in the county of St. Louis and State of Minnesota, have invented certain new and useful Improvements in Railroad-Rail Joints, of which the following is a specification, reference being had therein to the accompanying drawing.

10 This invention relates to railroad rail joints and has for its principle object the providing of a more efficient and durable joint than heretofore known.

Another object is to provide a joint with 15 automatic tightening or calking means whereby the joint becomes more firm and secure during use.

Another object is to provide a joint which may be assembled in different ways under 20 different circumstances whereby to increase its adaptability.

Other objects and advantages of the invention will appear in the further description thereof.

25 Referring to the accompanying drawings forming part of this application, in which like reference characters indicate like parts:

Figure 1 is a full sized transverse sectional view through a railroad rail adjacent 30 one of my improved joints.

Figure 2 is a reduced side elevation of the joint on the common fish plate side or inside of the rail,

Figure 3 is a similar view on the opposite 35 or outside of the rail, with the bracing plate removed therefrom,

Figures 2 and 3 illustrate opposite sides of one of my improved completely assembled joints in which two wearing or base 40 plates are employed under each end of the abutting rails and upon the spaced ties supporting same.

Referring to Figures 1, 2 and 3 of the drawings, 1 and 2 represent the abutting 45 ends of two railroad rails, 3 a common fish plate, 4 my improved fish plate, 5 the brace plate, and 6 the wearing plate.

The novelty in my present invention resides more particularly in the form of fish 50 plate 4 and wearing plate 6 and the manner of applying the same, to which end the latter is provided with three parallel spaced up-standing ribs 8, 9 and 10, all of which extend the entire width of the plate, except 55 that the rib 10 has formed vertically there-through the necessary spike holes.

The intermediate rib 9, the inner face of which when in service abuts the edge of the base of the rail and which latter is firmly fitted between it and the ribs 10, is 60 provided upon its inner face with an offset or cut-away channel 11 extending approximately one-half its entire height and adjacent the overhang or gib 12 of the rib 9. This cut-away portion is to provide for 65 the application of the wearing plate to the base of the rail directly transversely, that is to say, the plate may be slipped in under the rail transversely and at an heeled up angle thereto with the near upper corner 70 of the base of the rail extending within the cut-away channel 11 to permit of the upper inner corner of the rib 10 passing the lowermost farther corner of the base of the rail over it until the plate may be brought up 75 snugly under the rail, and for this purpose it may be necessary to have the uppermost inner corner of the wearing plate adjacent the rib 9 slightly cut-out as indicated in dotted lines at 13, Figure 1, to permit of this 80 action, but I have found in practice that there is sufficient resiliency in the plate to permit of their being forcibly applied, resulting in a snug fit without the aid of such latter provision.

85 The improved fish plate 4 is made heavy in cross section and when resting in position upon the inclined upper face of the base of the rail extends slightly above the bulb or tread of the rail and this extending portion 90 is highest in the middle of the fish plate as illustrated at 14, the same gradually sloping toward the ends of the plate where the latter are substantially flush with the top of the rail. This extended portion also overlaps 95 the rounded corner of the rail as at 15, but when in position and the plate is tightly engaged with the rail, the cut-away portion forming said overlapping is spaced slightly from the corner of the rail leaving an opening as at 16, the object of which will be hereinafter described. The remainder of the plate 4 is made to fit snugly within the side of the rail when drawn up tightly with the common bolts 7, it having a laterally extending flange 17 the entire length thereof except where cut-away for the reception of the rib 9 on the base plate, said flange being made to extend outwardly the full width of the rib 9. The cut-away portions or openings 18 for the gib or lip of the rib 9 are somewhat larger than necessary for the ac-

tual reception of the flange on the base plate so as to permit of tipping motion of the plate on the lower outer corner 19 of the rail as a fulcrum or pivotal point, and the opening 16 at the upper corner of the rail is also sufficient to permit of such rocking motion of the plate so that the upper edge of the brace plate 5 may be tipped outwardly for dismantling the joint when the bolts 7 are slackened off, or for assembling them in like manner, it being understood that the bracing plates 5 are the full length of the joint and are angular in form with their horizontally disposed base portions 20 resting entirely upon the upper face of the wearing plate 6 intermediate of the ribs 9 and 8 and impinging against the inner edge of the inner face of the latter rib. The flange 17 of the fish plate being thus recessed for the rib 9 on the base plate provides against a possible tendency of longitudinal creeping of the fish plate so that there can be no movement longitudinally the rail of any portion of the joint independently of the remainder thereof, this anti-creeping feature being considered very essential by many prominent railroad engineers, and the flange 17 may be formed with a turned down extension intermediate of the ties if so desired.

There are suitable spike holes through the base portion of the bracing plate which register with the spike holes in the wearing plates so that the common spike is made to hold the two firmly in position, and it may be desirable to make the angle of the bracing plate slightly more acute than that necessary to fit snugly intermediate of the arcuately shaped shoulder 21 in the outer upper face of the fish plate 4 and the angle in the wearing plate so that the lower outer edge of the base of the bracing plate may normally heel up slightly as indicated in dotted lines at 22, thus providing a certain amount of space for resilient action in the breathing of the joint when the rolling stock passes thereover.

Now in providing the overhang 15 of the upper edge of the tread portion of the fish plate 4 an automatic calking of the joint takes place during the passage of the wheels thereover, as such calking action is well known to those versed in the art, and as the space 16 becomes more completely calked by continued use, the joint continues to grow more firm and substantial.

As before stated the tread of the fish plate 4 is elevated centrally somewhat above the plane of the tread of the rail, which provides for a slight elevation of a wheel passing thereover which simultaneously compensates for the breathing or depressing of the joint together with the desired calking process.

It is apparent that a joint thus used will eventually become practically inseparable

without the destruction of some portion thereof, however portions of such used joint may become available for subsequent use upon worn rails on a less important road bed, as the aim in this structure is to provide the most ideal form of joint for main line construction.

While I have shown a common fish plate 3 associated with my improved rail joint, it is to be understood that the same may be dispensed with if desired and the nuts of the bolts 7 drawn up tightly directly against the web of the rail and also in either event it is desirable to have the brace plate 5 sufficiently long to cover the heads of the bolts to prevent their becoming dislodged in case of the nuts working loose.

Having thus described my invention, what I claim and desire to secure by Letters Patent, is:

1. A rail joint comprising a base plate having means for engagement with the base of a rail comprising two parallel ribs spaced apart a distance equal to the width of the base of the rail and one of said ribs overlapping the edge of the base of the rail, a transversely disposed upwardly extending rib adjacent one end of the plate and spaced from the rail holding ribs, a fish plate having a bulb thereupon extending upwardly approximately level with the top of the rail, a groove in the lower outer corner of the bulb, a brace plate slidably engageable intermediate of said groove and the rib on the base plate, means for holding the latter and the brace plate cooperatively united and a common fish plate on the opposite side of the rail joint united with the other fish plate by common through bolts.

2. A rail joint comprising a base plate having means for engagement with the base of a rail comprising two parallel ribs spaced apart a distance equal to the width of the base of the rail and one of said ribs overlapping the edge of the base of the rail, a transversely disposed upwardly extending rib adjacent one end of the plate and spaced from the rail holding ribs, a fish plate having a bulb thereupon extending upwardly approximately level with the top of the rail, a groove in the lower outer corner of the bulb, a brace plate engageable intermediate of said groove and the end rib of the base plate, means for holding the latter and the brace plate cooperatively united, and common through bolts for holding the fish plate and rail together.

3. A rail joint comprising two spaced base plates each having means for engagement with the base of a rail comprising two parallel ribs spaced apart a distance equal to the width of the base of the rail and one of said ribs overlapping the edge of the base of the rail, a transversely disposed upwardly extending rib adjacent one end of

each plate and spaced from the rail holding ribs, a fish plate having a bulb thereupon extending upwardly approximately level with the top of the rail, a groove in the 5 lower outer corner of the bulb, common through bolts for holding the fish plate and the rail together, a brace plate of sufficient length to cover all of the bolts and extending from the outer extremities of both base 10 plates and engageable intermediate of said groove and the end rib of the base plates, and means for holding the latter and the brace plate cooperatively united.

4. A rail joint comprising in combination 15 a base plate having means for engagement with the base of a rail, a brace plate cooperatively engageable with the outermost end of the base plate, a fish plate intermediate of the brace plate and the rail and 20 cooperatively engageable with the brace plate, said fish plate being held normally in contact with the rail by means of common through bolts, and means whereby the uppermost portion of the fish plate may be

adjusted for applying or removing the brace 25 plate.

5. A rail joint comprising a base plate having means for engagement with the base of a rail comprising two parallel ribs spaced apart a distance equal to the width of the 30 base of the rail, one of said ribs overlapping the outer edge of the base of the rail, a transversely disposed upwardly extending rib at the end of the plate and spaced from the last mentioned rib, a fish plate upon the 35 outside of the rail extending upwardly adjacent the side of the bulb of the rail, an inclined bracing plate engageable intermediate of the end rib of the base plate and the uppermost outer face of the fish plate, 40 and common through bolts for holding the rail and the fish plate together.

In testimony whereof I hereunto affix my signature in the presence of two witnesses.
